US0D1026843S

(12) **United States Design Patent** (10) **Patent No.:** **US D1,026,843 S**
(45) **Date of Patent:** **** May 14, 2024**

(54) **VIDEO COMMUNICATION TERMINAL**

(71) Applicant: **SHENZHEN ELECTRON TECHNOLOGY CO., LTD,**
Guangdong (CN)

(72) Inventors: **Cheng Zhuang**, Shenzhen (CN);
Yonghong Li, Shenzhen (CN)

(73) Assignee: **SHENZHEN ELECTRON TECHNOLOGY CO., LTD,**
Guangdong (CN)

(**) Term: **15 Years**

(21) Appl. No.: **29/862,600**

(22) Filed: **Dec. 10, 2022**

(51) LOC (14) Cl. **14-02**

(52) U.S. Cl.

USPC **D14/130**

(58) **Field of Classification Search**

(57) **CLAIM**

The ornamental design for a video communication terminal, as shown and described.

DESCRIPTION

FIG. 1 is a perspective view of video communication terminal showing my new design;

FIG. 2 is another perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines in the drawings depict portions of the video communication terminal that form no part of the claimed design.

1 Claim, 8 Drawing Sheets
